ELECTRON BEAM CONVERGING DEVICE

Michiaki Ito, Tokyo, Japan, assignor to Nippon Electric Company, Limited, Tokyo, Japan, a corporation of Japan

Filed Jan. 29, 1959, Ser. No. 789,846

Claims priority, application Japan Feb. 25, 1958

3 Claims. (Cl. 313—84)

This invention relates to a beam focussing device which makes use of periodically varying magnetic flux as the converging means for the electron beam. For example, it relates to an electron beam converging device used in microwave beam tubes, particularly traveling wave tubes.

Electron beam converging devices previously proposed attempt to provide a magnetic flux along the axis of the beam which varies in strength substantially as a sine wave. This is done by arranging ring shaped magnets in opposition, that is with the like poles adjacent one another. Generally, also, there are provided magnetic pole pieces between the adjacent magnets to bring the magnetic field effects down closer to the tube carrying the electron beam. In such arrangements it is necessary to provide for coupling an external circuit to the slow wave structure within the tube. This is generally done by waveguides which extend at right angles to the tube. These waveguides then introduce a gap in the magnetic structure and so disturb the continuity of the magnetic field introducing certain distortion.

It is an object of the present invention to provide a beam focussing device of the magnetic type which will permit the discontinuity of the magnetic field to be avoided.

According to a feature of this invention there is provided a magnetic beam focussing device made up of a plurality of magnetic units, each of these units includes two magnets with adjacent poles of opposite polarity separated by a region of high magnetic reluctance. These units are assembled with adjacent poles of opposite polarity facing one another. Preferably, also magnetic pole pieces are interposed between adjacent magnetic units.

The above-mentioned and other features and objects of this invention and the manner of attaining them will become more apparent and the invention itself will be best understood by reference to the following description of an embodiment of the invention taken in conjunction with the accompanying drawings, in which:

FIG. 1a is a sectional diagrammatic representation of a magnetic focussing unit of the prior art;

FIG. 1b is a curve illustrating the variation in magnetic flux along the axis of the beam in FIG. 1a;

FIG. 2 is a diagram illustrating the type of disturbances which may be introduced by the structure of FIG. 1a;

FIG. 3a is a view, particularly in cross section, illustrating an embodiment of the present invention; and

FIG. 3b is a curve showing the variation in magnetic flux along the beam axis obtained with the structure shown in FIG. 3a.

Turning now to FIG. 1a, there is shown a magnetic focussing assembly comprising a plurality of magnets 1 in the form of rings. These magnets are positioned with adjacent pole faces of like polarity. Intermediate each of the magnets are provided pole pieces of magnetic material 2. The electron beam 3 of tube 4 is shown traversing the axis of the magnet assembly. Waveguides for coupling to the external circuits are shown at 5.

By reference to FIG. 1b, it will be seen that over the greatest length of the assembly of FIG. 1a the flux variations along the axis follow substantially a sine wave. However, the variation departs from this sine wave characteristic along the assembly in the area in which the

2

coupling waveguides 5 cause interruption of the uniform magnetic structure.

Turning to FIG. 2, the nature of the disturbance for the beam can be better understood. In this figure the beam penetrating factor of the magnetic field is plotted as ordinates and the operating voltage for the electron beam as abscissa. For the greater part of the length of the magnetic element, that is, where the sine wave variation is maintained, a stable penetrating factor is obtained as shown by curve 6. The penetrating factor increases smoothly to nearly 100% penetration beyond the area 7, which illustrates the lower limiting voltage for operation of the beam tube. However, in the areas of disturbance, represented by the waveguides 5, there is produced an excessive variation in the penetration factor with the changes in operating tube voltage as illustrated in the curve 8.

These disturbing effects are undesirable. Methods of reducing or avoiding these effects have been proposed by the addition of other magnetic devices external of the waveguide 5. These additional structures, however, are difficult to construct and are quite critical, requiring extreme care in accurately adjusting them.

According to the present invention, the difficulties outlined above with respect to the prior art may be overcome by the novel magnetic focussing structure. An example of this new structure is illustrated in FIG. 3a. There are provided individual magnetic units composed of separate permanent magnets 1' and 1'' separated by a spacing of high magnetic reluctance 9. This spacer may preferably be in the form of some non-magnetic material in the interest of the construction of a unitary assembly. Magnets 1' and 1'' are arranged in magnetic aiding relation. That is, with adjacent poles being of opposite polarity. It will, therefore, be apparent that at each end of these units there will be poles of opposite polarity. A plurality of these units are then assembled with poles of opposite polarity on the separate units, adjacent one another. Intermediate these units are provided magnetic pole pieces 2 preferably made of soft iron or some such material. The permanent magnets may be made of some high magnet steels, although in the preferred construction some of the permanent magnet type of ferrites are used.

With this type of magnetic assembly, it will be apparent that the magnetic field in the axis of the assembly will not be a pure sine wave but will have ripples at the peaks of the waves producing a field along these axes corresponding to a sine wave variation with a superimposed third harmonic as shown in FIG. 3a by curve 10. It is possible to have the magnetic flux density B2 in the form shown by selection of the desired magnetic material, controlling the dimension ratio of the magnets and the spacing, and adjusting the inner diameters of the pole pieces. The magnetic flux B2 can then be represented by the following equation:

$$B2 = \cos \frac{2\pi Z}{L} - \frac{1}{2} \cos \frac{2\pi Z}{L}$$

where L is the length of the magnetic unit including elements 1', 1'', and 9, and Z is the magnetic strength of the field at the axis. It has been found that a field closely following this equation may be determined theoretically or experimentally, having in mind the various parameters of the elements forming the assembly.

For example, magnets 1' and 1'' may be made of permanent magnet ferrites with an outside diameter of 0.89 L, an inside diameter of 0.27 L, and a space of 0.18 L. Such a structure has been found to obtain a flux distribution substantially as described above.

In the application of this invention, the spacing by the elements 1' and 1'' may be so chosen that the waveguide

width is substantially the same as this spacing. The wave-guide couplers may then be inserted between two magnets of a single unit in place of the normal spacers 9. Accordingly with this type of construction, there will be no discontinuity in the magnetic field at the points at which the external couplings are applied.

In an arrangement utilizing ferrite magnets of the dimensions given above, it is found that substantially the same effect can be obtained using a spacing between the magnets of 8 mm. as is produced in a prior art structure such as shown in FIG. 1a with a magnetic unit of 10 mm.

In accordance with this invention, all of the magnets 1' and 1'' may be uniform in dimension and magnetization, and the assembly can, therefore, be readily made. It is quite easy, therefore, to construct focussing devices in accordance with this invention with the desired characteristics.

While I have described above the principles of my invention in connection with specific apparatus, it is to be clearly understood that this description is made only by way of example and not as a limitation to the scope of my invention as set forth in the objects thereof and in the accompanying claims.

What is claimed is:

1. A beam focussing device of the magnetic type comprising a plurality of magnetic units, each unit including a pair of magnets positioned with their adjacent poles

of opposite polarity separated by a non-magnetic material extending over a fixed region of high magnetic reluctance, whereby poles of opposite polarity exist at opposite ends of said unit, annular pole pieces of magnetic material positioned between the poles of adjacent magnetic units and said units being positioned in tandem so that their adjacent poles are of like polarity whereby a periodic field is provided along the longitudinal axis of said magnetic units.

2. A beam focussing device according to claim 1 wherein said pair of magnets are each in the form of a hollow cylinder.

3. A beam focussing device according to claim 2 further comprising electrical wave transmitting devices extending from the external surface of one of said units into the hollow of the cylinder defined by said unit through said fixed region.
